UNITED STATES PATENT OFFICE

GEORGE W. JONES, OF CLEVELAND, OHIO.

STEAM ROCK-DRILL.

SPECIFICATION forming part of Letters Patent No. 373,894, dated November 29, 1887.

Application filed May 2, 1887. Serial No. 236,869. (No model.)

To all whom it may concern:

Be it known that I, GEORGE W. JONES, of Cleveland, in the county of Cuyahoga and State of Ohio, have invented a certain new and Improved Steam Rock-Drill; and I do hereby declare that the following is a full, clear, and complete description thereof.

My invention relates to that class of rock-drills which are operated by steam-power; and the improvement consists in the peculiar construction and arrangement of the operative parts used in connection therewith.

That the invention may be more fully understood, reference will be had to the annexed specification and the accompanying drawings, in which—

Figure 1 represents a vertical section through the steam cylinder and chest. Fig. 2 is a horizontal section of the same in line *x x*. Fig. 3 is a face view of the upper cylinder-head, showing the parts located therein. Fig. 4 is a vertical section of the said head in line *y y*, Fig. 3. Fig. 5 is a plan view of the head. Fig. 6 illustrates a plan view of the cylinder with the upper head removed. Fig. 7 is a side elevation of Fig. 1.

Like letters of reference refer to like parts in the several views.

In the drawings, A represents the steam-cylinder provided with the chest B and the heads C D, which may be either bolted or otherwise secured in place. Inside the said cylinder is placed the reciprocating piston E, with a conical extension, E', which is for the purpose of actuating the valve F, by means of the bolt G and lever H, attached to the eccentric-spindle I.

The steam-ports *a* and *b* and exhaust-port *c* are formed in an entirety with the cylinder A, and are in open relation with the steam-chest face *d* or valve-seat, respectively. The ports *a b* are under control of the slide-valve F, and lead alternately live steam from the steam-chest into the cylinder and exhaust-steam from the latter into the exhaust-port *c*. The pipes K and K' alternately lead live steam to and exhaust-steam from the cylinder A.

Located within and extending transversely across the steam-chest B is the spindle I, above referred to. The same is held and guided in relation with the chest by means of the pivot *e* and the stuffing-box L, which has a screw-

threaded connection with the steam-chest B. This spindle I extends through the stuffing-box, and is provided with a hand-wheel, M, the purpose of which will be hereinafter explained. The lever H is fitted to the central and eccentric part, I', of said spindle I, one arm of which lever engages in the groove *f* of the valve F, and the other in a slot formed in the head of the bolt G, as seen in Fig. 1. The spring N, arranged within the cover g, causes the bolt G to be at all times in contact with the piston-extension E' after steam is shut off.

When steam-pressure is within the chest, the steam would then alone suffice to hold the bolt G in contact with the piston-extension E' and vibrate the lever H for the operation of the valve F, so that steam may alternately be admitted to the upper or lower side of the piston in the cylinder for the reciprocating motion of the piston and its attachments.

The necessary rotation of the drill secured to the outer end of the piston-rod E" (not shown in the drawings) is obtained by the combination and arrangement of the following elements, which are located within the top head, C, as seen in Figs. 1, 3, and 4. Said head C and the bottom head, D, are secured to the cylinder A by the bolts O and P. Interposed between the upper face of the cylinder A and that of the head C is the plate Q, on and by which the ratchet-wheel R is suspended, as seen in Fig. 1. The stem R' of said wheel is square and fits into a socket, R'', inserted in the piston E. By this means the piston E, while reciprocating within the cylinder A, is connected with the ratchet-wheel at every point of its stroke. The stem R admits of the reciprocation of the piston, and imparts to the same the rotation of the ratchet-wheel R. The feed attachment of said wheel R is arranged to operate automatically, and for that purpose steam-power is utilized to actuate the pawl S for the rotation of the wheel R. Said pawl S is pivotally attached to the piston T, Figs. 3 and 4, and moves with the latter within the small cylinder C', projecting in a horizontal position from out the head C. The open end of the small cylinder C' is provided with a removable cap or plug, U, which admits of the insertion or removal of the piston T from that side. The opposite side of said cylinder C' is in open relation with the interior of the head

C, and also with that of the cylinder A, by means of the openings *h* in the plate Q. Thus when through the port *a* steam is admitted into the cylinder A above the piston it causes the downward or outward stroke of the same. The steam-pressure will then, also, be active within the head C and force the piston T toward the rear of the cylinder C'. The piston T while moving backward withdraws the pawl S for engagement into the next tooth of the ratchet-wheel R. The spring *s*, located within the piston T and seated on the pawl S, forces the same toward the wheel and assures engagement with the next or following tooth. To prevent the piston T from being thrown with undue force against the cap U, the former is provided with a cylindrical projection, *t*, fitting into the recess V of the cap U, as seen in Fig. 4. By this means the steam which is active within the recess V has the tendency to retard the stroke of the piston T and act as a cushioning device for the latter.

As illustrated in the drawings, steam is admitted through port *a*, and the piston is on its outstroke until the valve F travels beyond the port *a*. Steam is then supplied through port *b* to the under side of the piston for the return-stroke. As soon as the steam enters into the cylinder by the way of the port *b*, the port *i*, communicating with the interior of the cylinder below the piston, will also be filled with steam and carry the same to the top of cylinder A, into the horizontal port *j*, and from thence through the opening *j'* into the cylinder C', between the piston T and the cap U, which results in a forward movement of said piston and pawl and a consequent turning of the wheel R, which, by means of its square stem R', turns the piston and rod E'' with the drill attached thereto.

The eccentric part I' of the spindle I, Figs. 1 and 3, is for the purpose of setting the valve F in relation to the ports *a* *b*. By means of the hand-wheel M the spindle I can be turned

to either side, thereby throwing the eccentric part I' more or less to one side or the other, according to the desired movement of the main piston.

As stated, the drill is rotated on the upstroke of the piston by the mechanism as set forth. It may, however, be arranged to rotate during the downstroke of the piston without departing from the essential features of my invention.

The above-described steam rock-drill is mounted and operated upon a truck or frame of the usual style and construction, and by means of the ing A', Figs. 1 and 6, connection may be had with a feed-screw commonly employed with this class of drills.

What I claim as my invention, and desire to secure by Letters Patent, is—

1. In combination with the valve-gearing of a steam rock-drill, the slide-valve F, bell-crank lever H, pin G, spring N, and the conical extension E', all arranged within the steam-chest 65 and cylinder, substantially as set forth.

2. In combination with the slide-valve of a steam rock-drill, a bell-crank lever fitted to an eccentric spindle, with bearings within the steam-chest, and a hand-wheel outside thereof to turn the spindle for the lateral adjustment of the valve in relation to the steam-ports, for the purpose described, and substantially as shown.

3. The combination of the cylinder A, head C, plate Q, interposed between said cylinder and head and provided with openings to receive the stem R' of the ratchet-wheel R and allow the passage of steam from the cylinder into the head, piston E, pawl S, with piston T, 80 spring *s*, and the ports *i j*, all substantially as shown, and for the purpose described.

In testimony whereof I affix my signature in presence of two witnesses.

GEORGE W. JONES.
